UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LET-OFF MECHANISM FOR LOOMS.

Application filed January 3, 1927. Serial No. 158,534.

This invention relates to a mechanism for controlling the let-off of warp from the warp beam of a loom.

It is the general object of my invention to provide an improved automatic let-off mechanism, by which a very even and uniform tension will be maintained on the warp during the operation of the loom. A further object is to provide means by which the warp may be conveniently adjusted by hand, without changing the tension adjustment of the automatic let-off mechanism.

My invention further relates to arrangements and combinations of parts which will be hereinafter described and more particularly pointed out in the appended claims.

A preferred form of the invention is shown in the drawings in which

Fig. 1 is a left hand side elevation of a loom having my improved let-off mechanism applied thereto;

Fig. 2 is a view similar to Fig. 1, but showing the parts in a different operative relation;

Fig. 3 is a partial sectional front elevation, taken along the line 3—3 in Fig. 1;

Fig. 4 is a detail sectional rear elevation, taken along the line 4—4 in Fig. 1;

Fig. 5 is an enlarged bottom view of certain parts of the let-off mechanism, looking in the direction of the arrow 5 in Fig. 1;

Fig. 6 is a similar view but showing the parts in a different relation and looking in the direction of the arrow 6 in Fig. 2;

Fig. 7 is a detail view of a portion of the warp beam connection, looking in the direction of the arrow 7 in Fig. 3;

Fig. 8 is a detail plan view, looking in the direction of the arrow 8 in Fig. 7;

Fig. 9 is a detail sectional view, taken along the line 9—9 in Fig. 3;

Fig. 10 is a view similar to Fig. 7 but showing a modified driving connection, and

Fig. 11 is a detail sectional elevation, taken along the line 11—11 in Fig. 10.

Referring to the drawings, I have shown a portion of a loom frame 20 supporting a rock shaft 21 for swords 22 which carry the usual lay 23 and reed 24. The warp W is wound on a warp beam 25 (Fig. 3) commonly having a friction pulley 26 secured thereto, and provided with a gudgeon 27 on which the warp beam is supported, the parts

thus far described being of the usual and standard construction.

For the purpose of my invention, I have provided a short shaft or driving member 30 rotatable in a bearing bracket 31 supported by a stand 32 (Fig. 1), such stand being bolted to the loom frame 20. The bracket 31 is vertically adjustable in a guideway on the stand 32, as shown in Fig. 9, and is connected thereto by bolts 33 extending through slots 34 (Fig. 3). By this construction the warp beam may be adjusted vertically as the size of the beam is reduced, thus bringing the delivery point of the warp to the desired elevation, and making it possible to operate the loom without using a separate whip-roll, a construction which is at times extremely desirable.

The shaft or driving member 30 is provided with an arm 35 at one end thereof, having its outer end forked at 36 to receive the end of a lug 37, adapted to be secured by a bolt 38 (Fig. 3) to the inside of the rim of the usual friction pulley 26. The shaft or driving member 30 is provided with an axial recess 39 to receive and center the gudgeon 27.

If the pulley 26 is of exceptionally small diameter, it may at times be desirable to reverse the arrangement, securing the lug 37 to the outer face of the pulley 26, as indicated in Figs. 10 and 11.

A worm wheel 40 is keyed to the outer end of the shaft 30 and is engaged by a worm 41 (Fig. 2) fixed on a worm shaft 42. The shaft 42 is freely rotatable in bearings 43, 44 and 45 formed on a stand 46. At its upper end, the stand 46 is provided with a slot 47 through which extends a stud 48 mounted on a bracket 49 secured to the frame 20. The lower rear end portion of the stand 46 is loosely pivoted on the shaft 30, as indicated in Fig. 3.

With this construction, the worm 41 maintains a continuous driving engagement with the worm wheel 40 in every vertical position of the warp beam.

The worm shaft 42 has a limited axial sliding movement in its bearings 43, 44 and 45, and the lower rear end of the shaft 42 is engaged by the short arm of a tension lever 50, pivoted at 51 on the stand 32. Adjustable weights 53 are supported on a hanger

54 which may be positioned in any one of a series of notches 55 on the lever 50.

The weights 53 thus tend to slide the shaft 42 upward and to turn the warp beam rearward or in the direction of the arrow *a* in Fig. 1, thus tensioning the warp *W*. At the upper front end of the worm shaft 42 I have provided a hand wheel 57 having a handle 58, and also having ratchet wheel 59 formed on its rearward face.

A feed pawl 60 (Fig. 5) is loosely pivoted on a stud 61 fixed on a supporting member 62 which in turn is pivoted to swing about the axis of the worm shaft 42. The supporting member 62 is provided with spaced bearing portions 63 and 64 which embrace the shaft bearing 45 (Fig. 1) and thus maintain the member 62 in a definite axial position. The member 62 is also provided with a laterally projecting arm 66 (Fig. 4) having a stud 67 to which is pivoted the upper end of a link 68. The lower end of the link is pivoted at 69 to an arm 70 fixed to the rock shaft 21 previously described. A light spring 71 (Fig. 5) is attached at one end to the pawl 60 and at its opposite end to the supporting member 62, and normally maintains the pawl in the inoperative position shown in Fig. 5.

30 Having described the details of construction of my improved let-off mechanism, I will now describe the operation thereof.

In the normal operation of the loom, the weights 53, acting through the tension lever 50, apply pressure to the lower rear end of the worm shaft 42, forcing the shaft upward and forward in its bearings, and at the same time causing the worm to have a direct action on the worm wheel, like a rack and pinion, turning the warp beam in the direction of the arrow *a* in Fig. 1, and placing the desired tension upon the warp *W*.

The parts will remain in this relation as the warps *W* are gradually woven into the cloth 45 and drawn forward by the usual take-up mechanism (not shown).

During this forward movement of the warp, the warp beam will be slightly rotated, forcing the worm 41 and worm shaft 42 downward and rearward, and slightly raising the weights 53 but maintaining the warp tension substantially unchanged. During all of this time the feed pawl 60 is being regularly oscillated by the link 68 55 from the rock shaft 21, but the ratchet teeth 59 are displaced forwardly and upwardly so as to be out of the path of the feed pawl, as indicated in Figs. 1 and 5.

Gradually, however, the worm 41 and 60 worm shaft 42 are forced downward and rearward as the warp beam is rotated forwardly, and after a while the ratchet teeth 59 are moved into the path of movement of the pawl 60. As soon as the pawl engages 84 one of the ratchet teeth, the pawl will be

rocked on its pivot 61, as indicated in Fig. 6, thus taking firm hold of the ratchet teeth and turning the worm 41 like a screw in the teeth of the worm wheel 40. Such movement raises the shaft 42 and lowers the weights 53, while at the same time maintaining the uniform tension upon the warp *W*.

When the worm shaft 42 has been thus rotated sufficiently to move the ratchet teeth 59 out of the path of travel of the pawl 60, the let-off movement will cease and the parts will thus be restored to the normal running relation shown in Fig. 1.

The let-off mechanism is thus automatic 80 and self-adjusting and continuously restores the tension weights 53 to operative relation with the warp beam. The hand wheel 57 and handle 58 are conveniently located so that the weaver may adjust the warp tension or release the same at any time, as required by the conditions of operation, and this may be done without disturbing the adjustment of the tension lever 50 or the weights 53 thereon.

During the continued operation of the loom, the diameter of the warp beam will gradually decrease, and this change may be taken care of as usual by removal of more or less of the weights 53 or by the adjustment of the hanger 54 to a different notch 55 in the tension lever.

Having thus described my invention and the operation thereof, it will be seen that I have provided a very simple and convenient let-off mechanism which requires a minimum of attention and which will maintain uniform tension on the warp during the operation of the loom, while at the same time it may be very conveniently adjusted by hand for such purposes as may be necessary.

I do not wish to be limited to the details herein disclosed otherwise than as set forth in the claims, but what I do claim is:

1. In a loom, a warp beam having a worm wheel thereon, a worm engaging said wheel, a forwardly extending shaft to which said worm is secured, bearings for said shaft in which said shaft is axially slidible, an automatic feeding device for said shaft, a tension lever engaging the rear end of said shaft and effective to move said shaft axially forward, thereby normally rendering said feeding device inoperative, and a handle at the front end of said shaft by which said shaft may be manually adjusted.

2. In a loom, a warp beam having a worm wheel thereon, a worm engaging said worm wheel, a forwardly and upwardly extending shaft to which said worm is secured, bearings for said shaft in which said shaft is axially slidible, a ratchet on said shaft at its upper front end, a pawl to advance said ratchet, means to regularly move said pawl,

tension means normally effective to hold said ratchet out of the path of said pawl but permitting said pawl to become operative upon continued taking-up of the warp, 5 and manual means positioned at the upper front end of said shaft and readily accessible for manual adjustment of the warp tension.

3. In a loom, a warp beam having a worm wheel thereon, a vertically adjustable bearing for said warp beam, a worm engaging said worm wheel, a forwardly and upwardly extending shaft to which said worm is secured, bearings for said shaft, a stand for said bearings pivoted on the axis of said 15 worm wheel and having a pin and slot connection at its front end with the loom frame, and a feeding device for said shaft, operative thereon at the front end thereof, and in every adjusted position of said stand.

20 4. In a loom let-off mechanism, a ratchet, and a feed pawl mounted for movement

about the axis of said ratchet, said ratchet being movable axially into and out of the path of movement of said pawl under the control of the warp tension, and said pawl 25 being yieldingly movable toward said ratchet when engaged thereby.

5. In a loom let-off mechanism, an axially movable ratchet, a supporting member mounted for movement about the axis of 30 said ratchet, a feed pawl pivoted on said member, and yielding means to normally position said feed pawl substantially parallel to the face of said ratchet, said ratchet being movable by warp tension into the path 35 of said pawl, and said pawl, upon engaging said ratchet, being rocked on its pivot to cause a full engagement therewith.

In testimony whereof I have hereunto affixed my signature.

OSCAR V. PAYNE.
